UNITED STATES PATENT OFFICE.

JOHN BACHMANN, OF HOBOKEN, NEW JERSEY.

IMPROVED SUBMARINE VESSEL AND LIFE-BOAT.

Specification forming part of Letters Patent No. 44,380, dated September 27, 1864.

To all whom it may concern:

Be it known that I, JOHN BACHMANN, of Hoboken, in the county of Hudson and State of New Jersey, have invented new and useful Improvements in Submarine Vessels and Life-Boats; and I do hereby declare the following to be a full and exact description of the same, reference being had to the accompanying drawings, making part of this specification, in which—

Figure 1 is a plan of a submarine vessel illustrating my invention, partly in section, as indicated by the line x x . Fig. 2 is a sectional elevation of the same, the plane of section being indicated by said line x x . Fig. 3 is an end elevation, this view also being made partly in section as represented by the line y y . Fig. 4 is a front end elevation representing the wings or side pieces, to be hereinafter described, in a closed condition and the vessel submerged. Figs. 5, 6, and 7 are detached sectional views illustrating my improved method of attaching and operating the propelling devices. Fig. 8 is a detached view representing an improved construction of hinge to be employed in connection with my improved vessel.

Similar letters of reference indicate corresponding parts in the several figures.

This invention consists in certain improvements in vessels designed to be submerged and rapidly propelled while in this condition for discovering and raising sunken vessels, safely depositing torpedoes, and for other purposes.

The invention is also well adapted for the purpose of a life-boat.

In order that others skilled in the art to which my invention appertains may be enabled to fully understand and use the same, I will proceed to describe its construction and operation.

In the accompanying drawings, A represents a vessel, the main body of which is constructed in nearly cylindrical form and tapered toward the ends, so as to promote the rapidity of its progress through the water and adapt the necessary evolutions thereof to be performed with readiness and celerity. This vessel or main body A rests on a flat-bottomed hull or section, A', which may serve to render the sailing and floating movements of

the vessel steady and regular, and thus provide for the occupants as comfortable a conveyance as other boats or vessels of small capacity.

In the front end of the vessel A is provided a lookout, A², which, as illustrated in the drawings, may consist of a number of glass disks inserted in a strong frame of iron or other metal, which is employed to prevent the breaking of the glass should the vessel accidentally strike an obstacle.

On the upper part of the vessel A and at the respective sides of a suitable opening formed therein are mounted wings B², the ends of which are provided with plates B' B', which are adapted to slide within the triangular wings B² B², secured to the end pieces, B³ B³. The wings B B² are attached, respectively, to the vessel A and end pieces, B³, by hinges B⁴, which are of peculiar construction and effectually prevent the entrance of water into the vessel without the necessity of employing any additional appliance. One of these hinges and the manner of attaching the wings are clearly illustrated in Fig. 8. The form of the hinge may approximate more or less to that of a hollow cylinder, and that portion of each of the wings which occupies the hinge is made in corresponding cylindrical form, as shown at b', so as to fit snugly therein and form a perfectly water-tight joint. The hinge is provided with a longitudinal opening, as illustrated, which admits of the ready insertion of the cylindrical portion b' of the wing, and adapts said wing to be turned on its axis b' in an inward or outward direction to an extent of forty-five degrees, (more or less,) for the purpose to be explained. The plates B' are attached to the wings B by hinges B⁴, similar in construction to those above described.

C represents a longitudinal piece or beam, to each side of which is secured a strip, c, of rubber or other suitable impervious material. When the wings are to be closed to adapt the vessel for submarine operations, the end wings, B², fold in against the sections B³ and the side wings, B, against the beam C in such manner that the entrance of water at top is effectually prevented.

Between the wings B and near the ends thereof are screws D, (one shown in Fig. 2,)

which are mounted and adapted to rotate in suitable bed-plates, D', secured in the upper part of the vessel A.

On each of the screws D is adapted to work a sliding collar, D², to which are jointed arms D³, the latter being jointed at their opposite ends to the wings B.

The respective screws D operate in connection with a worm, D⁴, on the shaft D⁵, and a toothed wheel, D⁶, keyed upon the lower end of the screw, adapts the same to rotate simultaneously with the shaft D⁵, the latter being adapted for rotation through the medium of a crank-handle, D⁷, gear-wheel d, and pinion d', with which devices the shaft D⁵ may be provided at one or both ends, as may be desired. Thus, by the rotation of the crank-handle D⁷, the threaded collar D² may be caused to run either down or up on the screw D, and thereby operate the arms D³ in such manner as to open or close the wings B B². When the wings are folded in, the apparatus will float in an almost submerged condition, as represented in Fig. 4, or be prepared for entire submersion when submarine operations are to be performed; but when the wings are open the apparatus will rise and float in the position in Fig. 3.

E E E represent propelling devices, which consist individually of a pair of leaves secured to an arm, E', by means of small hinges e, similar in construction to those indicated by the letter B⁴. The inner end of the arm E' is inserted into a socket, E⁷, on the arm E⁸, and retained therein by a pin, e', the said arm E⁸ occupying a conical cavity or aperture, E², in the side of the vessel A, and being inserted into and operated through the medium of a shaft, E³, which shaft rests against and effectually closes the inner end of the conical aperture E². The shaft E³ is fitted to rotate in a box or block, E⁴, which may be turned in such manner as to place the shaft E³ in either a vertical, horizontal, or any oblique position it may be desired to have it assume in order to vary and regulate the manner or direction in which its corresponding propeller E acts. Each shaft E³ may have a rotary reciprocating motion imparted to it by a handle, E⁶, and by the turning of these handles E⁶ the propellers E may be oscillated with great facility and rapidity.

The socket E⁷ provides means for the ready replacement of the propellers E should they become broken or deranged.

F may represent a series of propellers secured upon a shaft, F', which passes transversely through the vessel A at the central portion thereof. This shaft F' is adapted to

be turned completely round, whereby the propellers F may be readily made to act upon the water in an upward, downward, or other direction. These propellers F are of the same construction as the propellers E.

G represents the rudder, which may be operated in any suitable manner.

On the forward end of the vessel A is formed a groove, a, in which may be placed a cord, which holds a torpedo or other explosive device.

H H represent arms, which may be operated from within the vessel in such manner as to remove the cord from the groove a and deposit the explosive device in the place where it is desired to have it explode.

The wings B B² and end sections, B³, are studded with a series of glass disks, b³, through which submarine observations may be taken in all directions.

I I represent ventilating-tubes, in the upper ends of which are valves i i, which may be opened and closed at will by means of a cord or rope wire.

Operation: When the vessel is to be lowered beneath the surface of the water, (the wings having been closed in the manner described,) this may be accomplished by working the propellers F in such manner as that they will act upon the water in an upward direction, the propellers F assisting in the operation and providing means by which may be regulated the degree of inclination in which the apparatus descends. When the vessel is to be brought to the surface, the position of the propellers is reversed to effect this object.

If it be desired, the vessel may be converted into a sail-boat, when the wings are in an open condition, by substituting a mast for either of the ventilating-tubes I, or employing the tubes themselves in this capacity.

Having thus described my invention, the following is what I claim as new and desire to secure by Letters Patent:

1. The wings B B² and plates B', constructed, arranged, and operating in the manner described, and employed in connection with the vessel A A', as and for the purposes set forth.

2. The combination of the block E⁴, shaft E³, and handle E⁶, constructed and arranged as described, and employed for operating the propellers E, in the manner set forth.

3. The hinges B⁴ e, formed in one piece and adapted to prevent the entrance of water, substantially as herein described.

JOHN BACHMANN.
